UNITED STATES PATENT OFFICE.

EDWARD E. ROSE, OF SWISSVALE, PENNSYLVANIA, ASSIGNOR TO WESTINGHOUSE ELECTRIC & MANUFACTURING COMPANY, A CORPORATION OF PENNSYLVANIA.

TROLLEY FROG.

1,406,285.

Specification of Letters Patent. Patented Feb. 14, 1922.

Application filed May 6, 1919. Serial No. 295,070.

To all whom it may concern:

Be it known that I, EDWARD E. ROSE, a citizen of the United States, and a resident of Swissvale, in the county of Allegheny and

5 State of Pennsylvania, have invented a new and useful Improvement in Trolley Frogs, of which the following is a specification.

My invention relates to trolley-conductor devices and particularly to approach members 10 for frogs, crossings and similar structures.

One object of my invention is to provide a device of the above indicated character that shall be simple and durable in construction 15 and inexpensive to manufacture.

Another object of my invention is to provide an approach for a trolley-conductor device that, with its co-operating members, shall comprise a relatively small number 20 of parts and be readily mounted in operative position on a conductor by the use of a simple tool, such as a hammer.

In frogs, crossings, section breaks, splices and any similar device for attachment to 25 a trolley conductor, a renewable approach member, functioning as an arcing tip and wearing guard therefor, is highly desirable to prolong the life of the device and prevent interrupted service. This renewable 30 member should be permitted of mounting and demounting in as short a space of time and with as great facility as it is possible to attain, consequently, nuts, bolts and other devices, that may become locked together 35 by rust, should be avoided.

The handling of small parts, especially where more than one of such parts is used, is very objectionable by reason of the amount of time and labor required thereby.

40 Climatic conditions and the hazards usually attending trolley-line installations make it highly desirable, if not imperative, that workmen employed in such work be given facilities to perform their work with 45 the utmost simplicity of movements.

It is, therefore, my aim to provide a removable approach member, for a frog or other trolley-conductor device, and a composite holding and wedging member therefor 50 that may be readily moved to and from their operative positions. To this end, I provide a frog or other device having means for the reception of a holding member that may be placed on the frog by a very simple hand 55 movement and an approach member that

may be conveniently slipped into operative relation thereto. After this, a few well directed blows of a hammer will serve to secure the members together.

Figure 1 of the accompanying drawings 60 is a side elevational view of one end of a trolley frog and an approach member embodying my invention; Fig. 2 is a view taken along the line II-II of Fig. 1, and Fig. 3 is a view similar to Fig. 1 but partially in 65 section.

A frog 1, for the reception of a trolley conductor 2 and only one approach end 3 of which is shown, comprises a body portion 4 of substantially channel or U-section in 70 which the conductor is disposed and to which the latter may be attached in any suitable manner. An extension member 5, preferably of malleable material, projecting from the end 3, has an inverted channel 75 portion 6 for embracing the conductor 2, a plain end face 7 that engages the end 3 and a centrally-projecting portion or tongue 8 disposed in the channel 4 above the conductor 2. Oppositely and outwardly-projecting lugs or flanges 9 on the upper edge of the channel portion 4 at the end 3 support a holding member 10 that is provided with a longitudinal depending wedge portion 11 on its inner surface. End portions 12 of the 80 member 10 embrace the flanges 9 and may be rigidly secured with respect thereto and the portion 11 secured in wedging relation to the tongue 8 by placing the member 10 over the end of the frog and driving the latter home with a few well directed blows of a hammer. The wedge portion 11, in addition to a longitudinal slope at its upper edge, slopes also thereto in transverse directions in conformity with the top of the tongue 8 85 in order to automatically align the member 10 with respect to the member 4 and the conductor 2 when the approach member 5 is being placed in position.

Reinforcing ribs 13 permit the member 10 100 to be of substantially minimum weight and maximum strength and effect economy of material therein.

The device is extremely simple and durable in construction, effective in operation, 105 easy to manipulate and, since the wedge portion 11 and the holding member 10 are integral, reduces the number of loose parts to substantially a minimum.

While I have shown and described a par- 110

ticular form of my invention, changes may be effected therein without departing from the spirit and scope thereof, as set forth in the appended claims.

5 5 I claim as my invention:

1. A trolley-conductor device comprising a body member having outwardly-extending oppositely disposed horizontal edge portions, and a wedge member for securing a conductor in position with respect thereto disposed above the body member and having portions extending downwardly around said edge portions.

15 2. A trolley-conductor device comprising a body member of substantially channel shape for the reception of a conductor, said body member having outwardly-extending transverse portions adjacent to its edges, an approach member having a portion projecting into the end of said channel, and a wedge member engaging all of said portions to hold said members together.

25 3. A trolley-conductor device comprising a body member of substantially channel shape for the reception of a conductor, said body member having outwardly-extending transverse portions, an approach member having a tongue projecting into the end of said channel and a wedge member formed to co-operatively engage said portions and said tongue to position said members on a conductor.

35 4. A trolley-conductor device comprising a body member of substantially channel shape for the reception of a conductor, said body member having outwardly-extending transverse portions, an approach member

having a tongue projecting into the end of said channel, and a member formed to engage said portions and having a wedge portion for engagement with said tongue.

40 45 5. A trolley-conductor device comprising a body member of substantially channel shape having outwardly-extending transverse projections, an approach member having a portion in said channel, and a member having substantially underhung hook portions embracing said projections and a portion of substantially wedge shape engaging the approach member.

50 55 6. A trolley-conductor device comprising a body member, an approach member therefor, and a wedge engaging said members, said approach member and said wedge member having interfitting portions.

60 65 7. A trolley-conductor device comprising a body member, an approach member therefor and a wedge member for holding said members together, said approach member and said wedge member having a substantially tongue-and-groove connection to each other.

8. A trolley-conductor device comprising a body member, an approach member therefor and a longitudinally-slidable wedge member for holding said members together, said approach member and said holding member having a substantially tongue-and-groove connection to each other.

In testimony whereof, I have hereunto 70 subscribed my name this 23d day of April, 1919.

EDWARD E. ROSE.
